United States Patent Office.

JOHN LE FERRE, OF CHARLESTOWN, MASSACHUSETTS.

Letters Patent No. 78,213, dated May 26, 1868.

IMPROVED METHOD OF FORMING CARRIAGE-AXLES.

The Schedule referred to in these Letters Patent and making part of the same.

TO ALL WHOM IT MAY CONCERN:

Be it known that I, JOHN LE FERRE, of Charlestown, in the county of Middlesex, and State of Massachusetts, have invented certain Improvements in Axles for Carriages, &c., of which the following is a full, clear, and exact description, reference being had to the accompanying drawings, making part of this specification, in which—

Figure 1 is a plan of a portion of my improved axle.

Figure 2 is a longitudinal section through the same.

Figure 3 is a transverse section on the lines y y of figs. 1 and 2.

It has heretofore been customary to construct the axle of a carriage, &c., from one homogeneous piece of metal, which is rolled or drawn down to the size and form required. In the event of the iron containing any impurities, the journal of an axle so constructed, when subjected to a severe strain, is frequently broken.

To obviate the above-mentioned difficulty is the object of my invention, which consists in the method of constructing an axle of two or more pieces of iron or steel, laid longitudinally, and welded together, by which means the grain of the metal is crossed, and the several layers or pieces are closely united together, in such manner as to successfully resist a very considerable strain without breaking, the metal, when obliged to yield, simply bending, whereby it may again be readily straightened.

To enable others skilled in the art to understand and use my invention, I will proceed to describe the manner in which I have carried it out.

In the said drawings, A represents the outer portion of a carriage-axle, composed of four pieces, a , of iron or steel, laid longitudinally upon and thoroughly welded together. The piece thus made by the union of the several pieces a is tapered off, and the portion, b , forming the journal of the axle, turned down truly in a lathe, and provided with a shoulder, m m' , and a screw-thread, 5, for the reception of the nut, which keeps the wheel in place upon the journal, a suitable collar, 6, being provided, against which, or a washer, 7, the inner face of the axle-box or hub plays while revolving.

By the construction above described, should the iron or steel be defective at any particular point in one of the layers or pieces a , the piece or pieces a in contact therewith will serve to strengthen it, and the strain will be gradually and equally received, and distributed throughout the several pieces forming the axle; and should a concussion occur sufficiently severe to cause the axle to yield at all, it will simply bend, without breaking, and may readily be straightened out again.

It is evident car-axles, &c., may be constructed as above described, without departing from the spirit of my invention.

Claim.

What I claim as my invention, and desire to secure by Letters Patent, is—

The method herein described of constructing a carriage-axle, A, namely, by placing two or more steel or iron bars longitudinally, one upon the other, welding the same thoroughly together, then turning down the taper, b , with the shoulder m , thereon, and then adjusting on said taper, b , and against the shoulder m , a suitable collar, 6, and washer, 7, all in the manner substantially as set forth.

JOHN X LE FERRE,
his
mark.
